UNITED STATES PATENT OFFICE

MORRIS SHUGER, OF BALTIMORE, MARYLAND

BAIL-ATTACHING MEANS FOR CONTAINERS

Application filed July 25, 1927. Serial No. 208,175.

This invention relates to bail-attaching means, and more particularly those provided upon metallic vessels, for example containers used for paint.

5 The containers heretofore employed, such as sheet metal containers for holding paints, pigment, etc., have been provided with ears on each side near the top of the container through which the hooked ends of a bail are 10 passed in order to facilitate transportation of the container and its contents. The ears commonly employed for this purpose are constructed of a cupped piece of metal with a central perforation which are soldered to the 15 sides of the container. This soldering operation not only requires the use of skilled labor, but is expensive. Furthermore, these soldered bail-holding ears have proved unreliable, frequently breaking off in handling, 20 transportation or shipment; especially, when the container is filled with a heavy material such as paint.

Among the objects of this invention is the provision of simple, and readily adaptable 25 means whereby bails may be readily attached to cans or similar vessels, more particularly sheet metal containers, by inexpensive means, and without the need of skilled labor or special tools.

30 A further object of this invention is the provision of a bail-attaching means which can be readily assembled upon the container and which will overcome many of the disadvantages incident to the constructions here- 35 tofore employed.

Other further and more specific objects of this invention will become readily apparent to persons skilled in the art from a consideration of the following description when taken 40 in conjunction with the drawings wherein:

Fig. 1 is a side elevation showing my preferred bail-attaching device upon a can, the bail also being connected and in carrying position.

45 Fig. 2 is a section through the can shown in Fig. 1 below the top rim, a portion of the bail-holding member being broken away to facilitate illustration.

50 Figs. 3 and 4 are views similar to Fig. 2,

and illustrating certain modified detail constructions.

Referring to Figs. 1 and 2 showing my preferred construction, the bail-holding mechanism comprises the segments (1) and (2) of the circumferential band which are positioned at the top of the can (3) and just below the top rim or bead (4). Each of these sections (1) and (2) are provided at one end with an integral laterally extending stud or 55 projection (5) and at the other end with an integral laterally extending attaching member (6). The member of one section fits upon the stud of the other section, thereby locking the band about the can. In order to prevent 60 loosening and disengagement of the sections, the opening at the base of each attaching member is made slightly smaller than the largest peripheral portion of the stud, and when the attaching member is forced upon 65 the stud it will remain securely in place. The studs (5) are hollow and each is provided with an aperture (7) which when assembled registers with an aperture (8) in the attaching member when the latter is positioned on 70 the stud. The hooked ends of the bail (9) are introduced through these apertures and the bail will be held securely thereby.

In placing these circumferential bands upon the container (3), where the taper of the 75 container admits, the bail-holding member may be first assembled and is then forced upwardly from the bottom of the container against the top rim (4). Otherwise, the sections of the circumferential band are placed 80 around the can (3) and while in this position the caps are fastened upon the studs. It is to be understood that in order to fit the bail-supporting band securely to the can or container, the band or the sections must of proper 85 length so that when the caps are fastened on the studs, the band will tightly grip the container.

In the modification shown in Fig. 3, both 90 studs or projections 5' are formed on the ends of the same segment (1), and the attaching members 6' are formed upon the ends of the segment (2) of the circumferential band.

In the modification shown in Fig. 4, the 100

circumferential band (10) is made in one piece with a stud or projection 5" and attaching member 6" at each end. At the central portion of this circumferential band, a stud 5 or projection (11) is formed, and this stud contains the perforation (12) for receiving the hooked end of a bail, the other end of the bail being inserted through apertures in the stud or projection 5" and attaching member 10 6", which assume a position diametrically opposite to the stud (11), when the band is assembled. It will be seen that by this construction a single fastening means is used.

The bands are of resilient metallic material 15 and the studs and attaching members are formed integral therewith, as they are stamped out of the material forming the bands not readily broken away and do not interfere with the stacking of cans for storage 20 or transportation.

The present invention is not limited to the specific details set forth in the foregoing examples which should be construed as illustrative and not by way of limitation, and in view of the numerous modifications which 25 may be effected therein without departing from the spirit and scope of this invention, it is desired that only such limitations be imposed as are indicated in the appended claims.

30 I claim as my invention.

1. A bail holding member for cans comprising a split band for embracing the can body, means integral with the band and comprising a projection and an attaching member of like form, the former telescoped in the latter for securing the band in embraced position with respect to the can body, said projection and member having aligning apertures for receiving one end of the bail, and 35 apertured means integral with and projecting laterally from the band and spaced from the projection and member for receiving the other end of the bail.

2. A bail attaching device for cans comprising a band forming element for encompassing the body of the can, said element provided with diametrically disposed, integral, laterally extending, apertured means for receiving the ends of the bail to attach the latter to the 40 can body, the apertures in each of said means being disposed at right angles to the axis of the can, one of said means formed of two separable apertured parts of like form, one telescoped and substantially embraced by the 45 other and coacting therewith for maintaining said element in band-like form.

3. In a bail-holding member for cans and the like, a band formed of a pair of co-operating sections, each for semi-circumferentially 50 embracing the can body, and means comprising diametrically opposed studs and attaching members integral with the band sections for locking the latter securely around the can body, said studs and attaching members being 55 of like construction, the studs being telescoped

and embraced by the attaching members to form supports for the bail ends and held together by the latter.

4. In a bail-holding member for cans and the like, a metallic band formed of a pair of co-operating sections, each for semi-circumferentially embracing the can body, and means comprising diametrically opposed studs and attaching members integral with the band sections for locking the latter securely around the can body, said studs and attaching members being of like construction, the studs being telescoped and embraced by the attaching members, said studs and attaching members having openings for receiving the ends of the bail whereby the studs and attaching members are held together by and form supports for the bail ends.

5. A bail attaching device for cans comprising a band forming element for encompassing the can body, said element being provided with integral, laterally extending, apertured means for receiving one end of the bail in a direction to intersect the axis of the can body at right angles, and said element being further formed with a laterally extending, apertured projection and a laterally extending, apertured attaching member, said projection and member being of like construction, said projection telescoped and substantially embraced by said member for maintaining said element in band-like form, the aperture in said projection registering with the aperture in said member when the former is embraced by the latter, said registering apertures receiving the other end of the bail in a direction to intersect the axis of the can body at right angles.

6. A bail attaching device for cans comprising a band forming element for encompassing the can body, said element being provided with integral, laterally extending, axially apertured means for receiving one end of the bail in a direction to intersect the axis of the can body at right angles, and said element being further formed with a laterally extending, axially apertured projection and a laterally extending, axially apertured attaching member, said projection and member being of like construction, said projection telescoped and substantially embraced by said member for maintaining said element in band-like form, the aperture in said projection registering with the aperture in said member when the former is embraced by the latter, said registering apertures receiving the other end of the bail in a direction to intersect the axis of the can body at right angles.

In testimony whereof I affix my signature.

MORRES SHUGER.
